UNITED STATES PATENT OFFICE.

JOHN A. DUNCAN, OF HAMILTON, ONTARIO, CANADA, ASSIGNOR TO MERCURY MILLS, LIMITED, OF HAMILTON, CANADA.

GARMENT.

Application filed May 9, 1928, Serial No. 276,345, and in Canada July 2, 1927.

This invention relates to garments, and more particularly to heavy shirts of knitted fabric used in gymnasiums. This type of shirt is donned and doffed by the passage 5 of the wearer's head through an opening in the top of the garment, and my object is to provide a garment of this character which will fit neatly around the neck of the wearer.

I attain my object by securing a collar of 10 elastic material such as knitted fabric around the edge of the top opening in the garment, the ends of the collar being narrower in width than the remainder thereof to form a V-shaped opening at the front of the garment. This V-shaped opening is normally 15 closed by an overlying closure strip of elastic material which extends across the front of the top opening and is secured to the edge thereof. The constructions are hereinafter 20 more fully described and are illustrated in the accompanying drawings in which

Fig. 1 is a front elevation of part of my garment showing the collar and the overlying strip in their normal positions;

Fig. 2 is a similar view showing the collar and closure strip stretched to pass over the wearer's head; and

Fig. 3 a vertical section of the upper part of the garment.

In the drawings like numerals of reference indicate corresponding parts in the different figures.

1 is the body portion of the garment which is provided with the usual arm hole openings 2, the edges of which may be bound or short or long sleeves may be secured thereto. At the top of the garment is provided an opening 3 which is slightly dipped at the front of the garment and this dip extends from one shoulder portion 4 to the other shoulder portion 4^a. This dip in the opening results in the width thereof across the garment being increased when the latter is pulled to straighten out the front edge of the opening.

The size of the opening is thus increased sufficiently to enable the passage of the wearer's head therethrough to permit the garment to be donned and doffed.

A collar 5 formed of a band of elastic material such as ribbed knitted fabric is secured by the stitching 6 around the edge of the opening 3. This collar is formed of double

thickness to provide a rounded edge 5^a for contact with the wearer's neck and the bottom or free edges of the collar are cut to form 55 narrow ends or points 5^b. These ends are brought together at the front of the shirt and form a V-shaped opening or gap 5^c between the edges 5^a. By so cutting the collar a perfect fit around the neck is ensured and the 60 V-shaped opening facilitates the donning and doffing of the garment.

To substantially close the V-shaped opening 5^c and to hide the narrow ends 5^b of the collar I secure a closure strip 7 to the dipped 65 edge of the top opening 3. The closure strip is also formed of ribbed knitted fabric or the like of double thickness and has its ends 7^a narrower in width than the middle portion thereof. The latter portion is arranged centrally 70 of the V-shaped opening and the ends 7^a die away at the shoulder portions 4 and 4^a. The lower edge of the strip is secured either by the stitching 6 or a separate row of stitching to the edge of the top opening 3. 75

The rounded edge or neck opening 5^a of the collar 5 and the rounded edge of the closure strip 7 permit a greater lateral stretch at these edges than at the lower edges of these parts so that they may be stretched to conform to the size and shape of the top opening 3 when it is straightened out to pass over the head of the wearer as shown in Fig. 2. The collar and closure strip have a tendency to lie flat against the body of the wearer to form 80 a neat fitting garment as shown in Fig. 1.

What I claim is:

1. A garment having an opening at the top thereof; a collar having its ends narrower in width than the remainder of the collar and secured around the edge of the said opening; and a closure strip overlying the said narrow ends and secured to the garment. 90

2. A garment having an opening at the top thereof; an elastic fabric collar secured 95 around the edge of the said opening and provided with a substantially V-shaped opening to facilitate the donning and doffing of the garment over the head of the wearer; and a closure strip overlying the V-shaped opening and extending substantially from one shoulder to the other of the garment and being secured along the edge of the top opening. 100

3. A garment having an opening at the top

thereof adapted to permit the passage of the wearer's head therethrough; a collar having its ends pointed to form a V-shaped opening between them, the base of the collar being secured around the edge of the said opening; and a closure strip overlying the said V-shaped opening and being secured to the edge of the top opening.

4. A garment having an opening at the top thereof; an elastic fabric collar secured around the edge of the said opening and provided with a substantially V-shaped opening to facilitate the donning and doffing of the garment over the head of the wearer; and a closure strip tapering in width from the middle towards each end, and arranged centrally of the V-shaped opening.

5. A garment having an opening at the top thereof adapted to permit the passage of the wearer's head therethrough; a collar having its ends pointed to form a V-shaped opening between them, the base of the collar being secured around the edge of the said opening; and a closure strip extending substantially from one shoulder to the other of the garment and having its ends narrower in width than the middle portion thereof, the closure strip being secured along its lower edge to the edge of the top opening, the said middle portion being arranged centrally of the V-shaped opening.

Signed at Hamilton, Canada, this 3rd day of May, 1928.

JOHN A. DUNCAN.
